UNITED STATES PATENT OFFICE

ELWIN A. THOMAS AND FOREST A. THOMAS, OF WILLITS, CALIFORNIA

ILLUMINATED NAME AND NUMBER PLATE

Application filed March 18, 1926, Serial No. 95,808. Renewed November 14, 1929.

This invention relates to an improved illuminated name and number plate adapted to be fastened upon the outside of a dwelling or the like in proximity to a door of the same so as to clearly exhibit the name of the resident and the number of the residence, at night time, as well as by day.

The primary object of the invention is to provide a device of the above kind which is extremely simple and durable in construction as well as efficient for the purpose intended.

A further object is to provide a device of the above kind embodying slides adapted for removable reception of a plurality of letter and number panels whereby the required name and number may be provided for each individual device, as required.

A further object is to provide an illuminated name and number plate of the above kind embodying provision for supporting, convenient for access, a door bell controlling switch in such manner as to illuminate the same and thereby enable one to readily locate the same at night time.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts through the several views,

35 Figure 1 is a front elevational view of an illuminated name and number plate and door bell switch support constructed in accordance with the present invention;

40 Figure 2 is a bottom plan view thereof;

Figure 3 is an end elevation looking toward the left of Figure 1;

Figure 4 is a transverse section taken substantially upon line 4-4 of Figure 1;

45 Figure 5 is a rear elevation with the back plate member or wall removed; and

Figure 6 is a horizontal section taken upon line 6-6 of Figure 1.

Referring more in detail to the drawings, the present invention embodies a hollow relatively thick plate of generally rectangular form and preferably provided with beveled edges as well as composed of a pan-shaped body 5 having an integral front wall 6 and a removable back wall 7. The hollow plate is preferably of horizontally elongated form as shown and provided with horizontal upper and lower slots 8 and 9, respectively, in the front wall thereof and extending from end to end of the same. The front wall 6 is further provided with longitudinal grooves 10 along the horizontal or longitudinal edges of the slots 8 and 9, so as to form guideways for slidable and removable reception of frames 11 and 12. The lower slot and frame are relatively wider than the upper slot and frame, and the grooves 10 preferably open through both ends of the hollow name and number plate so that the frames 11 and 12 may be removed from either end of the same.

As shown, each frame is adapted for slideable removable reception of a plurality of panels 13 which serve as closures for the openings of the slide frames and certain of which have the desired indicia 14 thereon to be displayed and illuminated. As shown, certain of the panels 13 of the upper frame constitute letter panels adapted to be cooperatively associated to form the name of the resident of the dwelling, while the panels 16 of the lower frame are in the nature of number plates or panels adapted to be associated to constitute the residence number. The remaining panels of each frame are left blank as necessary, and suitable provision is made for the desired passage of light through portions of the panels for effecting their proper illumination. The panels may be stenciled opaque plates so as to allow the passage of light through the letters and numbers, or they may constitute transparent panels with

opaque numbers and letters suitably provided thereon by painting or the like. The latter form of the panels is preferable, and as shown in Figure 4, the slide frames are longitudinally grooved for reception of the panels 13.

As shown clearly in Figures 5 and 6, an electric light socket 15 is rigidly fastened within the hollow plate 5 and to the inner side of an end portion of the front plate 6 between the slots 8 and 9, and this lamp socket receives in its inner end an incandescent lamp bulb 17 adapted to be lighted for illuminating the interior of the plate 5 so that the rays of light will pass outwardly through the transparent portions of the panels 13 and thereby render the indicia 14 readily visible at night time. The lamp socket 16 is preferably of a type having a laterally swinging switch lever 17 by means of which the lamp 16 may be turned on and off as desired, and this switch lever projects outwardly through a slot 18 in the front wall 6 so as to be conveniently operated. In order to secure the lamp socket 15 in place, the same is provided along one side with a pair of studs adapted to seat against the inner face of the wall 6 as shown in Figure 6, at 19, and stud screws 20 are passed through openings in the wall 6 and threaded into the studs 19.

The other end of the portion of the wall 6 between the slots 8 and 9 is formed with an opening in which is fitted a door bell controlling switch 21 which is preferably of a type embodying a depressible push button 22 adapted to be depressed for closing the circuit of the door bell. This push button switch is disposed with its push button 22 exposed exteriorly of the hollow plate 5, and has base flanges or ears 23 seated against the inner surface of the wall 6 and bolted to the latter as at 24 so as to be rigidly secured in place. The part of the wall 6 between the slots 8 and 9 and between the lamp socket 15 and the switch 21 is provided with a relatively large opening through which the hand may be inserted for renewal of the bulb 16 when found necessary, and this opening is closed by means of a removable closure plate or panel 25.

The feed wires for the switch 21 and the lamp socket 15 are extended to the source of current and the door bell through an outlet opening in the back wall 7, and a suitable insulating bushing 26 is provided in this outlet opening for an obvious purpose.

The device is adapted to be flatly and rigidly secured against a wall of the dwelling adjacent the door of the latter, and for this purpose suitable attaching screws 27 are passed through aligned pairs of openings at the ends of the hollow plate 5 and in the front and rear walls thereof as shown in several of the views, the screws 27 being threaded into the wall of the dwelling.

The device above described provides a simple and durable name and number plate which is employed at day time with the switch 17 open and the light or lamp 16 unlighted, and at night time the switch 17 is closed for lighting the lamp 16 so that the name and number are effectively illuminated. In order to more effectively disclose the location of the door bell controlling switch 21, the latter is preferably provided with a transverse opening 28 as shown clearly in Figure 4, which opening is in line with the push button 22, and this push button 22 is formed of substantially transparent material such as glass so that the rays of light may pass outwardly therethrough from the interior of the plate member 5. In this way the exact location of the push button is made apparent.

From the foregoing description it is believed that the construction and operation as well as the advantages of the present invention will be readily understood and appreciated by those skilled in the art.

Minor changes may be made without departing from the spirit and scope of the invention as claimed.

What we claim as new is:—

1. In a structure of the character described, a flat hollow casing having a relatively large front wall plate and surrounding relatively shallow side walls, said front wall having a relatively wide slot formed therethrough and extending the length thereof and opening at each end through an end wall, said slot having the opposed faces of its longitudinal edges each provided with a groove, an elongated frame element designed to fit in said slot, a tongue formed along each longitudinal edge of said frame and designed to slide in one of the grooves and means whereby a plurality of indicia bearing panels may be mounted in the frame.

2. In a structure of the character described, a flat hollow casing having a relatively large front wall plate and surrounding relatively shallow side walls, said front wall having a relatively wide slot formed therethrough and extending the length thereof and opening at each end through an end wall, said slot having the opposed faces of its longitudinal edges each provided with a groove, a frame designed to fit into said slot, tongues formed along the longitudinal edges of said frame each designed to slide in a groove, said frame being formed throughout the length of the inner face of each longitudinal side member thereof, with a panel receiving groove and a slot through each end member thereof, and an indicia bearing panel designed to be inserted in a slot for positioning in the groove of the side members of the frame, substantially as described.

3. A structure of the character set forth, comprising a casing having its front wall provided with a slot and an opening below the slot, panels extending across the slot, and bearing indicia adapted to be illuminated from within the casing, an electric lamp socket arranged within the casing and secured to said wall with its lamp receiving end arranged adjacent said opening, and a closure plate removably secured to said wall over said opening.

10 In testimony whereof we affix our signatures.

ELWIN A. THOMAS.
15 FOREST A. THOMAS.
